UNITED STATES PATENT OFFICE.

JAMES C. LEAHAN, OF PHILADELPHIA, PENNSYLVANIA.

SPRING-GUIDE.

986,183.

Specification of Letters Patent. Patented Mar. 7, 1911.

Application filed April 23, 1910. Serial No. 557,162.

To all whom it may concern:

Be it known that I, JAMES C. LEAHAN, a citizen of the United States, residing at Philadelphia, in the county of Philadelphia and State of Pennsylvania, have invented a certain new and useful Spring-Guide, of which the following is a specification.

This invention relates, broadly considered, to springs such as are used in the construction of beds, couches, furniture, car-seats and the like, which are guarded or retained against lateral displacement.

The principal object of the present invention may be said to be the providing of a spring guide of neat, simple, durable, efficient and comparatively inexpensive construction, which while being free to contract and expand, is held and guarded against lateral movement.

20 A further object of the present invention is to provide a spring guide in which the plunger thereof, while free to move up and down is retained against rotary movement.

25 A still further object of the present invention is to provide a spring guide, which when applied to a bed, couch, furniture, car-seat, and the like, will in use enhance the comfort of the occupant due to the fact that the 30 weight of the occupant upon the spring will be evenly distributed in one direction only, that is downwardly and in contradistinction from downwardly and laterally.

Other objects of the invention relate to 35 the providing of general details of construction and arrangement of parts as will hereinafter more fully appear.

The invention consists of the improvements hereinabove described and finally 40 claimed.

The nature, characteristic features, and scope of the invention will be more fully understood from the following description taken in connection with the accompanying 45 drawings forming part hereof and in which:

Figure 1, is a view in elevation of a spring guide embodying the invention, Fig. 2, is a view in central section of the same, Fig. 3, is a top or plan view of Fig. 1, Fig. 4, is a view in cross-section taken upon the line 4-4 of Fig. 2, and Fig. 5, is a view in central section drawn to an enlarged scale, and illustrating the spring guide in contracted position.

55 Referring to the drawings, the spring guide of the invention is shown as comprising

ing generally speaking a base, a plunger working therethrough and a cushion between the base and plunger. As shown the base comprises a circular plate 1, provided with 60 apertures 2, for the reception of screws or the like whereby the base may be secured to place, a central aperture 3, being present, for a purpose to be presently described. Shown as formed integral with and 65 mounting the plate 1, is a portion 4, concentric with the plate 1, and forming a shoulder 5. The concentric portion 4, terminates in the upwardly extending standards 6, spaced as shown in Fig. 2, as of a 70 width equal to the width of the opening 3, in the plate 1. The standards 6, are bridged as at 7, to form a guide for the plunger parts of the spring guide. The part 7, is centrally apertured as at 8, for the passage 75 therethrough in its upward and downward movement of the circular stem 9, which is carried by the supporting disk 10, of the plunger parts. This stem 9, may be either formed integral or have other connection 80 with the said supporting disk 10. The stem 9, is provided with a key way 11, and the bridge part 7, is provided with a set screw 12, which normally engages said key way 85 whereby the plunger parts may move vertically with respect thereto. The lower portion of the stem 9, is provided with a laterally extending pin 13, in order to limit the upward movement of the plunger parts.

Fitted between the base and supporting 90 plate of the spring guide is a coiled spring 14, the shoulder 5, of the base and the shoulder 15, of the supporting plate serving to provide convenient means for retaining the spring in proper position. As clearly illustrated in the drawings, the supporting plate 10, comprises an annular ring 16, connecting which and the plate 17, which is arranged in a plane below that of said ring, and of smaller diameter, are inclined arms 18, 100 openings 19, being present between the said arms. In operation the plunger parts move upward and downwardly with respect to the base that is vertically and in contradistinction from laterally. In this connection, it 105 may be remarked, that the opening 3, serves to permit of the stem 9, passing down through the base parts. Thus the spring 14, always retains its shape and cannot be caused to act, or respond to lateral movement. Clearly when the spring guides of 110 the class above-described are used in connec-

tion with beds, couches, furniture, car-seats and the like they add to the comfort of the occupant by reason of the fact that they provide cushion like devices that readily respond to the weight of the occupant in up and down direction only. Obviously this is important because an article equipped with such spring guides will not sag due to spring displacement, but will always maintain a uniform surface.

What I claim is:

1. An article of the class recited comprising a centrally apertured base, a supporting element consisting of an annular ring having a plate arranged in a lower plane, said ring and plate being connected by arms, a stem depending from said plate and working through said apertured base, said stem being afforded vertical movement with respect to the base, but locked against lateral and rotary movement and a coiled spring between said base and supporting element.
2. An article of the class recited comprising a centrally apertured base, a pair of standards rising from said base, a centrally apertured bridge piece formed integral with said standards and spanning the base aperture, a supporting element consisting of an annular ring having a plate arranged in a lower plane, said ring and plate being con-

nected by arms, a stem depending from said plate and working vertically through the bridge piece but locked against lateral and rotary movement and a coiled spring arranged between said base and supporting element.

3. An article of the class described comprising a centrally apertured base, a pair of standards rising therefrom, a centrally apertured bridge piece, formed integral with said standards and spanning the base aperture, said bridge piece having a key, a supporting element consisting of an annular ring having a plate arranged in a lower plane, said ring and plate being connected by arms, openings being present between said arms, a depending stem carried by said plate having a key-way for coöperating with the key of the bridge piece working vertically through the bridge piece, a stop carried by said stem for limiting the upward movement of the supporting element and a coiled spring arranged between said base and supporting element.

In testimony whereof I have hereunto signed my name.

JAMES C. LEAHAN.
